UNITED STATES PATENT OFFICE.

LOUIS E. HOY AND HARMAN HOY, OF SILVER CREEK, NEBRASKA.

CAR ELEVATOR AND DUMPER.

SPECIFICATION forming part of Letters Patent No. 529,618, dated November 20, 1894.

Application filed February 26, 1894. Serial No. 501,546. (No model.)

To all whom it may concern:

Be it known that we, LOUIS E. HOY and HARMAN HOY, of Silver Creek, county of Polk, State of Nebraska, have invented certain new and useful Improvements in Car Elevators and Dumpers, of which the following is a specification, reference being had to the accompanying drawings.

Generally, the object of our invention is to produce improved devices for fixing a car or similar vehicle in a fixed position while the unloading process takes place, and in elevating it and dumping it.

Specifically, the object of our invention is to simplify the apparatus heretofore in use for the same purposes and to facilitate the operation thereof.

In the accompanying drawings: Figure 1 is an end elevation of a car with our apparatus in place. Fig. 2 is a side view thereof. Fig. 3 is a cross section. Fig. 4 is an end view of our apparatus, showing the car elevated.

Referring to the figures on the drawings: 1 indicates a section of track and 2 a dumping frame bridging the same.

3 indicates an elevated obstruction in the track located and measured so as to fill the space between the wheels 3^a of a car traveling on the track.

30 4 indicates the stanchions projecting upwardly from the axles 5 of the car.

6 indicates the end pieces of a swinging frame which are pivoted, respectively, as indicated at 7, to the upper beams and cross piece 8 of the frame.

35 9 indicates a coupling piece pivotally united to the end pieces of the swing frame and serving to cause them to move in unison. It is extended at one end and bent to form a hook 40 that may engage with either end of a catch

11 secured to the cross piece 8. The end pieces 6 of the frame are located so that when they are swung at right angles to the cross piece 8 they come directly over and touch the

45 tops of the stanchions 4. By this means the car may be held firmly in position, it being necessary for the wheels to rise over the obstruction 3 before it can move upon the track, this upward movement being prevented by

50 the engagement of the swinging frame with the stanchions. To limit the movement of the swinging frame to a position directly over

the stanchions, we provide upon one of the end pieces of the frame a depending stop piece 12 which strikes the side of the stanchion and 55 determines the position of the frame. A swinging frame is preferably provided on opposite sides of the dumping frame so that, when both are set in position, they afford between them guideways for the elevation of 60 the box 13 of the car.

14 indicates a dumping platform adapted to receive the load of the car at the upper limit of its travel, as indicated in Fig. 4.

15 indicates pulley guide-ways adapted to 65 receive the guide pulleys 16 securely pivoted, respectively, in suitable frames in the middle of each end of the car. The guide-ways are turned, as illustrated, so as to guide the pulleys from a vertical into a nearly horizontal 70 direction.

17 indicates projecting studs firmly secured to the bottom of the car. They have reduced necks 19 adapted to enter the jaw 20 of a pulley plate 21. The jaw 20 communicates with 75 a circular aperture 22 and is itself preferably downwardly inclined, as illustrated, for convenience of attaching the plate to the studs. When the end of the stud enters the aperture in the pulley block plate it is securely held 80 and free to revolve as long as there is an upward tension upon the pulley block.

23 indicates ropes securely fastened to the upper ends of standards 24, which afford seats for the pulley guides. The ropes are two in 85 number and are passed, respectively, around the pulleys 25 of the pulley blocks; thence ascending, each passes over guide pulleys 27 securely carried between uprights 28. Other guide pulleys 29, for example, conduct the 90 ropes away to a suitable elevating power, not illustrated.

30 indicates vertical stud guides, which serve to keep the studs in vertical line after being elevated by the action of the pulley ropes. 95 It will be perceived, therefore, that while the draft on the car exerts its influence upon the studs and in line with the pulleys as long as the pulleys are vertically above the studs, yet, when the pulleys, following their ways, 100 are carried out of the vertical position, the studs continue to ascend vertically and upset the car upon the pulleys as an axis, thereby discharging the load upon the platform.

When the power upon the pulley rope is released, the box of its own weight, guided by the pulleys descending through their ways, will return to the car and be ready for removal, to accomplish which all that is necessary is to unship the pulley blocks from the studs and to turn the swinging frames out of the way.

To insure the proper reseating of the car, after dumping, cleats 31 upon its sides may be provided in proximity to the stanchions.

We do not confine ourselves to the details of construction herein shown and described, but reserve the right to modify and vary them at will within the scope of the invention.

What we claim is—

1. The combination with a frame, track, obstruction thereon, and elevating mechanism, of a car provided with a detachable box and a horizontally swinging frame adapted to be swung above the car and prevent its rising over the obstruction and to act as a guide for the box when the same is elevated, substantially as specified.
2. The combination with a frame, track, obstruction and elevating mechanism, of a car provided with stanchions and a detachable box, and a horizontally swinging frame adapted to be swung above the stanchions of the car and stop mechanism adapted to retain the frame and stanchions in line whereby the stanchions and frame act as continuous guides

for the box when the same is elevated, substantially as specified.

3. The combination with a frame, of a car having centrally located terminal pulleys and studs secured to and below said pulleys, hoisting mechanism pivotally secured to the studs, pulley guide-ways deflected, as shown, and vertical stud guides, substantially as specified.

4. The combination with a frame, of a box provided with terminal studs, pulley blocks provided with plates having jaws and apertures communicating therewith and block elevating mechanism, substantially as specified.

5. The combination with a frame, track, obstruction thereon and a plurality of swinging frames, of pulley ways deflected, as shown, stud guides, a car provided with terminal pulleys and studs adapted to engage the pulley-ways to stud guides, respectively, pulley blocks adapted to engage the terminal studs and a means for elevating the pulley blocks, substantially as specified.

In testimony of all which we have hereunto subscribed our names.

LOUIS E. HOY.
HARMAN HOY.
